FRITZ SCHRÖTER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY

SYNCHRONIZING ARRANGEMENT FOR PICTURE TRANSMISSION

Application filed November 2, 1927, Serial No. 230,423, and in Germany November 24, 1926.

The present invention discloses a circuit arrangement adapted to insure synchronization of apparatus for picture transmission or similar apparatus for communication work in a simple manner. The basic idea of the invention consists in that, with the use of one and the same carrier wave, and apart from the picture impulses or other signals, a rhythm, cadence or synchronizing frequency for the drive of a synchronous motor at the receiving end is simultaneously transmitted by modulating the carrier wave with two audio frequencies, one of which in turn is modulated by the picture-element or picture-point frequency or signal frequency, while the second audio frequency is transmitted non-modulated. The said two audio frequency waves modulating the carrier frequency in this scheme must be spaced so far apart that no disturbing interference will result between the said two audio frequencies when rectified. Another essential point is that the audio frequency used for synchronization modulates the radio frequency only to a slight degree, and, if possible, only to an extent so that its intensity suffices for further amplification in the receiver apparatus.

One embodiment of the idea underlying the invention is illustrated in the accompanying drawing in connection with its application to picture transmission, in which Fig. 1 illustrates a transmitting system, Fig. 2 a receiving system adapted for cooperation therewith, Fig. 3 represents a modified form 35 of the transmitter shown by Fig. 1, and Fig. 4 represents a modification of the form of receiver shown by Fig. 2.

Now making reference to the accompanying drawings the picture or document to be transmitted is placed on a drum 1 which is subject in well known manner to a rotary and a shifting movement. A photo-electric cell 2 of annular form is adapted to explore the picture by the aid of light diffusely reflected from the picture surface. For this purpose, the light issuing from luminous source 3 is passed in the shape of a sharp pencil of light formed by the aid of a lens 4 through the central portion of the annular photo cell 2 adjacent the picture surface. For

driving the drum 1 a motor 5 is provided and the rotation thereof is transmitted through a toothed gear wheel 6 to the drum 1. At the receiving end there is a drum 7 which corresponds to drum 1 at the sending end. The drum 7 is arranged to revolve in synchronism with drum 1 and is subject to a similar displacement or shifting motion along its axis. As the means to control the light striking a light sensitive film suitable for recording the received picture, a Karolus cell 8 has here been assumed. The cone of light which passes between the condenser plates of the cell 8 is supplied from a light source 9. By the use of lenses 10 and 11, the path of the rays is rendered convergent twice, once for the passage through the cell 8 and the next time for punctiform illumination of the film. The Nicol prisms which cooperate with the Karolus cell and act as a polarizer and analyzer, respectively are denoted by 12 and 13. A motor 15 and a convenient toothed gear wheel, similar to that of the transmitter, is provided for driving the drum 7.

The two motors 5 and 15, for instance, may be of the shunt-wound direct current type, and their speed is adjusted by means of the series rheostats 16 and 17, respectively. However, it is a good plan to further provide for the motor 5 a speed governor (not shown) of any convenient kind, for instance, a Giebe type centrifugal governor adapted to keep the fluctuations of the speed of rotation inside acceptably low limits. However, at the receiving end the rotation of motor 15 by means of an additional synchronous motor 36 is kept in step with that of the shaft of motor 5. The transmission of the synchronizing audio frequency oscillations from the transmitter to the synchronizing motor 36 (which, as to the rest, may be of any desired form, for instance, it may consist of a La Cour wheel) is effected independently of the transmission of the picture-point frequencies in the following manner:

At the transmitter end, two low frequency generators are provided, one of which furnishes a carrier wave for the picture-point frequencies, while the other one furnishes the synchronizing frequency. The former may

be of any suitable kind, for instance, it may consist of a tuned thermionic valve generator, or a tuning-fork generator comprising amplification means, or else, as shown merely by way of example in the drawing, it may consist of an induction-type machine 18, the same in this case being driven by a motor 5. Fundamentally speaking, an alternative scheme would be to produce the picture-point carrier frequency by optical means instead of electrically by that, instead of 18, a revolving perforated disk is placed in the path of the rays issuing from 3, the carrier frequency being thus produced directly in the photo-electric cell 22, provided the speed of rotation and the number of holes are chosen conveniently. Hence, while the carrier frequency for the picture-point impulses may be produced also independently of the motor 5 by a great number of methods, the second audio frequency to be used for synchronization must bear an invariable relationship to the speed of rotation of the motor 5 or of the driving shaft, or in other words, it must vary in direct proportion to the variation of the motor speed. For this purpose, a second inductor 19 positively coupled with 5 and most suitably seated upon the same shaft, is provided.

The carrier frequency or wave supplied from the generator 18 for the picture-point frequencies is controlled or modulated in amplitude in the following way by the light brought to act upon the photo-electric cell 2: The photo-electric cell 2 forms the arm of a bridge arrangement which further comprises a variable condenser 21 and resistances 22 and 23. At the terminals of one of the diagonals of the bridge is supplied an alternating current potential furnished from the source 18 and conveniently regulated by a potentiometer 20. At the terminals of the other bridge diagonal this frequency subject to control of its amplitude by the light brought to act upon the cell 2, is taken off and fed to the control electrode of the amplifier tube 24. The object of the bridge arrangement as stated is to completely compensate the capacitive current flowing by way of the electrodes of the photo-electric cell 2 by the aid of condenser 21, so that, in the absence of illumination of the photo cell 2, no carrier alternating current potential will act upon the grid of the tube 24, it being understood, of course, that for the same purpose any other suitable compensation scheme could be employed. In series with the photo-electric cell there may be, further, provided a direct current potential upon which the alternating current potential taken off at 20 is superposed. If, then, a state of balance is established in the bridge when the cell is dark, the balance will be disturbed as soon as light strikes the said cell 2, with the result that a certain amplitude of the frequency furnished

from 18 will arise at the control grid of the tube 24, the value of said amplitude varying at the rhythm of the distribution of light and dark in the explored picture, in other words, the audio frequency furnished from 18, in turn, is modulated by the picture-point or picture-element frequency resulting from the changes in light and dark. If in the presence of the minimum illumination corresponding to the darkest portions of the picture the tone audible at the amplifier is adjusted to zero, this means that the intermediate carrier frequency furnished from 18 is fully modulated in a positive manner by the picture-element frequencies, and that the modulation is then just 100%.

The second audio frequency wave furnished from generator 19, on the other hand, and as already pointed out, should modulate the audio frequency carrier wave of the wireless transmitter only to a slight degree, to be more precise, only to such an extent that, compared with the noises due to stray, a sufficiently audible sound is heard at the receiver end, the latter being then further amplified until it represents an energy adequately high for the operation of the synchronous motor 36. In case it is not desired or it is impossible to obtain the full energy required for a synchronous motor 36 by means of amplification, the audio frequency tone received need be amplified only to such an extent as is required to operate a synchronous switch by means of which, by the aid of oscillation or rotating contacts, the opening and closing at the proper rhythm of a feeding circuit of the synchronous motor 36 is caused in the manner shown by Fig. 4. Easy modulation of the radio frequency of the transmitter by the audio frequency of the generator 19, according to the drawing, is effected by the means of a transformer 26 connected in the grid circuit of the tube 24, the primary current of said transformer being regulated to the desired strength. The battery 25 serves for providing the biasing potential on the tube 24. Another method of transmitting the frequency of generator 19 to the corresponding station, for instance, as shown by Fig. 3, consists in that this frequency is used for heating the filament of a tube which may be connected in the input amplifier cascade or the transmitter tube itself in the case shown, the filament of the amplifying tube 24 of Fig. 3 is heated from the generator 19 which is here shown as an alternator. The frequency is then intentionally transmitted to the receiver end in the form of what is known as the "filament tone", and the amplitude thereof is governed by the thermal inertia of the filament and by the adjustment of plate and grid biasing potential of the tube that is used, the amplitude being thus adjustable at will.

It is, of course, possible to introduce the

frequency of generator 19 also at some other point in the amplifier cascade between tube 24 and the modulator 28 of the radio frequency transmitter 29. In the drawing here shown, the frequency of the generator 18 modulated by the picture-element frequency and the non-modulated wave of the generator 19 operate at the proper amplitude relations, as hereinbefore pointed out, upon the grid of the tube 24, and they are further amplified by the photo-electric amplifier 27 until they have been raised to the amplitude required for the control of the modulator tube. As regards the difference in frequency of 18 and 19, it may be stated that, when 18 furnishes a carrier frequency of 5000 cycles, the one of 19 may be chosen at from 200 to 500 cycles. Assuming that at the transmission rate chosen, there is no need for recording picture-point frequencies above 2000 cycles, it follows that the channel or band of frequency modulated from source 18 and the photo cell 2 ranges between 3000 and 7000. Disturbances or interference in the recording of the picture, or in the synchronism due to the production of combination beat frequencies between the picture-element frequency and the frequency furnished by source 19 due to rectification are unable to arise when values as before suggested are chosen, not to mention the fact that combinations of the same kind could anyway be rendered harmless by the filter circuits employed at the receiver end.

At the receiving end, as shown by Fig. 2, there is first provided the wireless receiver 30 which may be worked in any suitable manner with radio frequency amplification, or with intermediate-frequency amplification, and which comprises further means for demodulation of the radio frequency oscillations. In the demodulation there is obtained a mixture of the two audio frequency oscillations furnished from sources 18 and 19 at the transmitter station, the former one representing the band formed by the picture-point frequencies. After sufficient preliminary amplification in the audio frequency amplifier 31, the band containing the picture-point frequencies is separated from the synchronizing wave by means of filters 32 and 33. In a simple case, it would also be sufficient to replace one of said filters, that is, 33 adapted to pass the higher frequencies by a condenser chain, while the other one, 32, adapted to pass the lower synchronizing frequency by a coil chain, or a high-pass and a low-pass, respectively. The two frequencies thus separated are thereupon raised finally to the requisite amplitude by amplifiers 34 and 35, respectively. The Karolus light valve is united with amplifier 35 in well-known manner, while the synchronous motor 36 is connected with the output circuit of amplifier 34. An alternative scheme, as

above pointed out, would be to drive the said synchronous motor 36 by means of a supply derived from a local circuit at the proper rhythm by the aid of a synchronous switch or vibrating rectifier 37 controlled from the output circuit of the power amplifier 34 as has been shown by Fig. 4. In this last named figure the vibrating rectifier 37 closes a local direct current circuit 38 by way of a transformer 39. In this manner synchronous alternating current power is locally generated for the motor 36.

I claim:

1. In a facsimile system, a light sensitive relay, means for introducing a carrier frequency potential in the output circuit of said relay, means for translating varying intensities of light and shade in a facsimile to be transmitted into varying intensities of current through said relay and modulating said carrier frequency thereby, a vacuum tube amplifier for amplifying said modulated carrier frequency, means for producing a separate synchronizing frequency, means for applying said synchronizing frequency to the filament member of said vacuum tube amplifier for heating the same and transmitting the said synchronizing pulse as a filament tone, means for transmitting said facsimile modulated carrier and said synchronizing energy, means for receiving said transmitted signals, and means at the receiving point for separating the facsimile modulated signals and the synchronizing signals and controlling a receiving system therefrom.

2. In a facsimile system, a support surface for a facsimile to be transmitted, a photo cell and means for influencing the photo cell by light varied in accordance with the intensity of light and shade in the facsimile to be transmitted, a bridge structure having the said photo cell forming one of the legs thereof, an adjustable capacity member in an adjacent leg thereto for balancing the capacity of the said photo cell during periods of zero illumination thereon, means for producing a carrier frequency, means for introducing said carrier frequency in said bridge structure across the diagonal between said cell and said variable capacity, means provided by said photo cell for modulating said carrier frequency, means for producing a separate synchronizing frequency, an amplifier, means for amplifying both said modulated carrier and said synchronizing frequency by said amplifier, means for transmitting each of said energies, means for receiving the said transmitted energies, means at the receiving point for distinguishing between the synchronizing energy and the picture frequency energy, and means for utilizing the picture frequency energy to produce at the receiver a reproduction of the transmitted facsimile, and means for utilizing the synchronizing

energy for producing synchronous operation of the receiver and the transmitter.

3. In a facsimile system, a support surface for a facsimile to be transmitted, a photo cell and means for influencing the photo cell by light varied in accordance with the intensity of light and shade in the facsimile to be transmitted, means for generating electrical oscillations of a carrier frequency, means provided by said photo cell for modulating the output of said generating means, means for generating a separate synchronizing frequency differing from the modulating frequency, an amplifier and means for applying oscillations of said carrier frequency, said modulation frequency and said synchronizing frequency to the input thereof, and means associated with the output circuit of said amplifier for transmitting the resultant output energy.
